UNITED STATES PATENT OFFICE.

JOHN M. FREEMAN, OF HICKORY, NORTH CAROLINA, ASSIGNOR TO DRAPER CORPORATION, OF HOPEDALE, MASSACHUSETTS, A CORPORATION OF MAINE.

WARP STOP-MOTION FOR LOOMS.

1,355,956.

Specification of Letters Patent.

Patented Oct. 19, 1920.

Application filed November 14, 1919. Serial No. 337,928.

To all whom it may concern:

Be it known that I, JOHN M. FREEMAN, a citizen of the United States, residing at Hickory, county of Catawba, State of North Carolina, have invented an Improvement in Warp Stop-Motions for Looms, of which the following description, in connection with the accompanying drawing, is a specification, like characters on the drawing 10 representing like parts.

This invention relates to warp stop mechanism for looms of the drop wire type. In this type of mechanism each warp end of the loom normally supports a drop wire 15 which when the warp end breaks falls into the path of a vibrating or reciprocating feeler, which being arrested thereby, initiates the action of suitable mechanism for stopping the loom. These drop wires are 20 slotted near their upper ends and supported upon suitable drop wire bars. The drop wire bars rest at their ends in open top seats in the loom frame in a common type of such mechanism.

25 When the whip roll is high, and when a harness frame moves to a high position, or when for any other reason a heavy tension is placed upon the warp in such a way as to jerk or lift the drop wires upwardly it 30 not infrequently happens that the drop wire bar is thrown out of its seat with consequent obvious disastrous results.

The object of this invention is to provide a simple and effective means for holding 35 the drop wire supporting bar or bars down in the seats, and preventing injury to the loom or disarrangement of the mechanism by having the drop wire bar or bars thrown out of the seats.

40 The nature and object of the invention will appear more fully from the accompanying description and drawings and will be particularly pointed out in the claims.

The drawings illustrate so much of an 45 ordinary type of loom as is necessary to a disclosure of the invention.

In the drawings—

Figure 1 is a view partially in vertical cross section and looking at the side of the 50 loom from the inside, many of the parts being broken away, and only sufficient parts being shown to disclose the invention.

Fig. 2 is a view on a larger scale similar to Fig. 1 of the parts immediately concerned with the invention.

Fig. 3 is a side elevation partially broken away of one end of the warp supporting bar, drop wire bars, their connections to the loom frame, and a preferred form of device embodying this invention. 60

As the present invention is concerned with but one detail of the loom it is sufficient to describe the construction and operation of the loom only in the most general way. 65

The warp ends 1 extend from the whip roll 2 past the lease rod 3, over the warp supporting bar 4, past the lease rod 5, through the heddles of the harness frames 6, through the reed 7 on the lay 8, to the 70 breast beam 9.

The warp supporting bar 4 is secured at its ends as by bolts 10 in brackets 11 secured to the loom sides and extends across the 75 loom.

In the form of warp stop motion illustrated, a pair of drop wire bars 12 and 13 are located one at each side of the warp supporting bar 4, and also extend across the loom and rest at their ends in open top 80 seats 14 formed in the brackets 11 which are connected to, or form a part of, the loom frame. The drop wires 15 are of the usual type, that is, thin, flat, slotted, metal members. These drop wires are threaded upon the drop wire bars 12 and 13 and each one hangs upon and is normally held elevated by a warp end. If a warp end breaks, the corresponding drop wire falls until it comes into the path of the constantly vibrating 90 feeler 16. The movement of this feeler is then arrested and this arresting of the feeler is utilized in a well known and familiar manner to stop the operation of the loom. 95

During the operation of the loom, it is often necessary to run a high whip roll. When this is done or whenever the arrangement is such that when the harness frame rises there is a tendency to lift the warp off the supporting bar, it not infrequently happens that the drop wires are jerked or lifted so high as to jerk or throw the drop wire bar upon which they are guided out from its seat in the loom frame. 100

To prevent this highly undesirable result 105 and to enable the warp stop motion to be operated satisfactorily under all positions of the whip roll and under all degrees of tension, and under any range of movement of the harness frames, this invention pro- 110

vides means for holding the drop wire in its seat.

A preferred construction for securing this result is illustrated and comprises a pair 5 of hold down devices which may be and preferably are each in the form of an inverted U-shaped metal clamp 17. One of these clamps is preferably located near each end of the drop wire bars. This clamp fits 10 over some rigid portion of the loom such for example as the warp supporting bar 4, and is so positioned that its ends 18 extend over the drop wire bars at each side of the warp supporting bar. This hold down device is removably secured or locked in position as by the headless set screw 19 passing therethrough and engaging the warp supporting bar.

This device is readily constructed and applied to existing looms, and efficiently secures the desired results. By simply unloosening the set screw 19 it is readily removed when it is desired to change or remove the drop wires.

25 Having thus described my invention what

I claim as new and desire to secure by Letters Patent is—

1. A warp stop mechanism for looms comprising a warp supporting bar, drop wire bars at the sides thereof seated in open top 30 seats in the loom frame, and an inverted U-shaped device removably secured to and straddling the supporting bar with its ends extending over the respective drop wire bars whereby the drop wire bars are prevented 35 from being thrown out of their seats.

2. A warp stop mechanism for looms comprising a drop wire bar, an open top 40 seat in the loom frame for the end of the drop wire bar whereby the drop wire bar may be removed from its seat by an upward lift, a hold down device extending when in operative position over the drop wire bar and holding the end thereof in its seat, and means for removably securing the hold 45 down device in its operative position.

In testimony whereof, I have signed my name to this specification.

JOHN M. FREEMAN.
